United States Patent Office

Des. 183,525

Patented Sept. 16, 1958

183,525

LOBSTER FORK

Bess Kaye, New York, N. Y.

Application November 20, 1957, Serial No. 48,563

Term of patent 14 years

(Cl. D54—12)

Fig. 1 is a front elevational view of a lobster fork, showing my new design;

Fig. 2 is a side elevational view of the same;

Fig. 3 is an enlarged sectional view taken on the line 3—3 of Fig. 1; and

Fig. 4 is a sectional view taken on the line 4—4 of Fig. 1.

I claim:

The ornamental design for a lobster fork, substantially as shown.
